F. M. FURBER.
FRICTION HEATED BURNISHING MACHINE.
APPLICATION FILED MAR. 20, 1915.

1,246,902.

Patented Nov. 20, 1917.

UNITED STATES PATENT OFFICE.

FREDERICK M. FURBER, OF REVERE, MASSACHUSETTS, ASSIGNOR TO UNITED SHOE MACHINERY COMPANY, OF PATERSON, NEW JERSEY, A CORPORATION OF NEW JERSEY.

FRICITION-HEATED BURNISHING-MACHINE.

1,246,902.

Specification of Letters Patent. Patented Nov. 20, 1917.

Application filed March 20, 1915. Serial No. 15,807.

To all whom it may concern:

Be it known that I, FREDERICK M. FURBER, a citizen of the United States, residing at Revere, in the county of Suffolk and State of 5 Massachusetts, have invented certain Improvements in Friction-Heated Burnishing-Machines, of which the following description, in connection with the accompanying drawings, is a specification, like reference 10 characters on the drawings indicating like parts in the several figures.

This invention relates to burnishing machines, and in particular to that type of machines in which the burnishing irons are 15 heated by friction.

In friction-heated machines heretofore used, great difficulty has been experienced in regulating the heat. A slight amount of wear between the rubbing surfaces alters the 20 pressure between them and, in consequence, the amount of heat developed, and the necessary adjustment is delicate and is frequently required. The constructions heretofore used do not lend themselves to easy 25 and fine adjustment. It is the object of my invention to simplify and improve the construction of devices of this class.

A feature of my invention is a device 30 capable of independent coarse and fine adjustment of the temperature of the burnishing tools.

Another feature of my invention is a device having a moving shaft, a holder and a friction device having a concave surface engaging the shaft, and adjustable while maintaining the same angular relation of the concave contact surface to the shaft.

Another feature of my invention is a device 40 for frictionally heating a plurality of tools so constructed and arranged that the relative temperature of the irons may be controlled.

Other features of the invention, comprising certain arrangements and combinations 45 of parts, will appear as the description proceeds and will be pointed out in the claims.

A preferred embodiment of the invention in a rotary tool burnishing machine is shown in the drawings. The machine there shown 50 has a tool carrying shaft having a ground and polished friction sleeve mounted on it between two rotary burnishing tools. The friction sleeve is engaged by a friction de-

vice which is adjustable along it between the two burnishing tools.

55

In the drawings;

Figure 1 is a perspective of the head of the machine, carrying the operating parts; and

Fig. 2 is a view, partly in section, of the 60 friction device.

The head 1 carries a bearing 2 in which rotates a shaft 3 driven by the pulley 4 and the belt 5. The shaft carries the burnishing irons 6, 7 upon its reduced outer end, 8. On 65 the shaft between the irons 6, 7 is mounted a sleeve 9 which is carefully ground, hardened and polished. The advantage of the sleeve 9 is that it obviates the preparation of a surface on the relatively large and 70 cumbrous shaft for frictional contact. The surface of shafting is not so finely finished as has been found advisable for friction surfaces. A stub shaft 10 is mounted in a lug 11 on the head 1 and extends parallel to the 75 shaft 3. The holder 12 is rotatably and longitudinally adjustable on the stub shaft 10 and is clamped in desired position by the set screw 13. The holder 12 has a smooth bore 14, having an enlargement 15 at one end. 80 Rotatably and slidably mounted in the bore 14 is a barrel 16, having a flange 17 and a knurled head 18. A spring 19 has one end mounted in the enlargement 15 and the other mounted against the flange 17. The holder 85 12 is split at 20 and the screw 21 can be set to clamp the barrel 16. The lower end of the barrel is internally threaded at 22, and its upper end 23 is bored out to the root of the thread. A threaded fiber rod 24 is 90 threaded into the barrel, and has a concave lower end 25 which fits the sleeve 9.

It is evident that a rotation of the barrel 16 by means of the head 18 will move the barrel up or down on the fiber rod 24, 95 increasing or diminishing the tension of the spring 19. The friction between the sleeve 9 and the fiber rod 24 may thus be adjusted within small limits and the generation of heat thereby controlled with considerable 100 nicety. The fiber rod is prevented from turning owing to the saddle-like grip which its surface 25 exerts upon the sleeve 9. The fiber rod has a small longitudinal hole 26 through which lubricant from the wadding 105 27 seeps slowly to the friction face 25. It is

obvious that adjustment of the body 12 along the rod 10 will alter the relative distances of the irons 6, 7 from the friction surface 25, and hence effect a control of the 5 relative temperatures of the two irons, as well as a coarse adjustment of the temperature of each iron.

The sleeve 9 is not necessary in a machine embodying my invention, as the friction 10 vice can be arranged to bear directly on the shaft 3 if desired. In the appended claims I have used the word "shaft" to denote comprehensively the rotating element which carries the tools, with such appurtenances as it 15 may have, and I do not intend therefore that the term be limited in meaning to the member 3.

Having described my invention, what I claim as new and desire to secure by United 20 States Letters Patent is:—

1. A machine of the class described having, in combination, a tool carrier, a tool carried thereon, and a friction device engaging said carrier and adjustable along it.

25 2. A machine of the class described having, in combination, a tool carrier, a tool mounted on said carrier, and a friction device engaging said carrier, constructed and arranged so that the distance of the point of 30 contact from the tool can be adjusted.

3. A machine of the class described having, in combination, a moving tool carrier, a plurality of tools mounted thereon, and a stationary friction device engaging the carrier between said tools.

4. A machine of the class described having, in combination, a moving tool carrier, a plurality of tools mounted thereon, and a friction device engaging the carrier between 40 said tools and adjustable along said carrier.

5. A machine of the class described having, in combination, a shaft comprising a

friction sleeve, a plurality of tools mounted on the shaft, and a friction device engaging said sleeve.

45

6. A machine of the class described having, in combination, a moving shaft, a holder, and a friction device comprising two relatively adjustable elements mounted in said holder, one of said elements engaging 50 said shaft.

7. A machine of the class described having, in combination, a moving shaft, a holder, and a friction device comprising two threaded elements mounted in said holder, one of said elements having a concave contact surface to bear against said shaft.

55

8. A machine of the class described having, in combination, a moving shaft, and a friction device having a concave contact surface bearing on said shaft, and adjustable while maintaining the angular relation of its concave contact surface to the shaft.

60

9. A machine of the class described having, in combination, a moving shaft, a holder, an element rotatably and resiliently mounted in said holder, and a friction piece in adjustable engagement with said element and engaging said shaft.

65

10. A machine of the class described having, in combination, a moving shaft, a holder and a friction element resiliently mounted in the holder, engaging the shaft, and having a lubricating channel.

70

11. A machine of the class described having, in combination, a moving carrier, a plurality of irons mounted thereon, and a friction device for heating the irons so constructed and arranged that the relative temperature of the irons may be controlled.

75

In testimony whereof I have signed my name to this specification.

FREDERICK M. FURBER.
